United States Patent [19]

Hiroki

[11] Patent Number: Des. 320,809

[45] Date of Patent: ** Oct. 15, 1991

[54] **SORTER ATTACHMENT FOR COPYING MACHINE**

[75] Inventor: Shin-ichi Hiroki, Machiya, Japan

[73] Assignee: Kabushiki Kaisha Toshiba, Kawasaki, Japan

[**] Term: 14 Years

[21] Appl. No.: 466,732

[22] Filed: Jan. 18, 1990

[30] **Foreign Application Priority Data**

Jul. 18, 1989 [JP] Japan 1-26321

[52] U.S. Cl. D18/42

[58] Field of Search D18/36-44; D14/110-114; 271/278, 287, 293; 355/322, 323

[57] **CLAIM**

The ornamental design for sorter attachment for copying machine, as shown.

DESCRIPTION

FIG. 1 is a top, front and right side perspective view of sorter attachment for copying machine showing my new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a rear elevational view thereof; and

FIG. 7 is a bottom plan view thereof.

FIG. 1

FIG. 2

FIG. 3

FIG. 4

FIG. 6

FIG. 5

FIG. 7
